UNITED STATES PATENT OFFICE.

DOMINIC F. CANNON, OF FORD CITY, PENNSYLVANIA, ASSIGNOR TO PITTSBURGH PLATE GLASS COMPANY, A CORPORATION OF PENNSYLVANIA.

PROCESS AND APPARATUS FOR MAKING SHEET GLASS.

Application filed December 14, 1927. Serial No. 239,903.

The invention relates to apparatus for making sheet glass, such as that shown in the patent to Lee Showers, No. 1,579,666 of April 6, 1926, although not limited to use 5 in a rolling machine of the particular type illustrated in the patent. It has for its principal object the provision of means for supporting and guiding the leading edge of the sheet onto and over the runway when 10 the rolling operation is started, although the apparatus may also be used as a cooling device after the rolling operation is under way. At the beginning of the rolling operation, the leading edge of the sheet has 15 a tendency to turn downward and catch upon the forward edge of the cooling platen, and after such edge has passed over the platen, it still tends, due to its plastic condition, to turn downward between the rolls 20 of the runway. The same difficulty obtains in those cases in which the first member of the runway consists of a roll instead of the platen. This condition has heretofore been taken care of by the use of hand tools, such 25 as bars or rods, and by the use of various other devices, such as plates which move along under the advancing end of the sheet and support it until it has hardened, so that it will not turn down and catch, but none 30 of these expedients has proven entirely satisfactory and the present invention is designed to accomplish the desired function with greater certainty and with less care and effort on the part of the operators. 35 Briefly stated, this is preferably accomplished by the use of air blasts, which are so directed that they turn the advancing plastic end of the glass sheet up slightly and hold it up and harden it while it is advancing 40 over the forward end of the receiving platen. The fluid preferably employed to lift the end of the sheet is air, but other gaseous fluids may be employed, such as steam. One form of apparatus for carrying 45 out the invention is shown in the accompanying drawings, wherein:

Figure 1 is a plan view of the apparatus with the upper sizing roll removed. Fig. 2 is a section on the line II-II of Fig. 1 50 with the upper sizing roll in position. And Fig. 3 is a view similar to Fig. 2, but on an enlarged scale.

Referring to the drawings, 1 is the large sizing roll supported upon the driven rollers 55 2 and 3, and 4 is the upper sizing roll also

driven and suitably water cooled. The glass to be rolled into a sheet is teemed into the space between the rolls, as indicated at 5 and the sheet 6 which is formed first passes onto the apron 7, forming the first element 60 of the runway and then over the rolls 8, which lead into the annealing leir, not shown.

The device for preventing the sheet from catching upon the forward edge 9 (Fig. 3) 65 of the platen or apron 7 comprises the transverse air pipe 10, to which are connected the supplemental pipes 11, 12, 13, etc. by means of the connections 14. The pipes 11, 12 and 13 are perforated along their sides, which 70 lie next to the roll 1, as indicated at 14a in Fig. 3, so that when air pressure is supplied through the pipe 10, the air blasts 15 are applied to the surface of the roll 1 just above the apron 7. These blasts are applied 75 at an angle, as indicated at Fig. 3 and are of such force that they lift the forward edge of the sheet slightly, so that when this edge reaches the end 9 of the apron, it is elevated 80 so that it will not catch upon such end. The 85 air blasts also have a cooling effect upon the end of the sheet which reduces its tendency to turn downward and engage the end of the apron 7. After the edge of the sheet has passed the end 9 of the apron, the flow 90 of air through the pipe 10 is shut off by means of the valve 16 and the operation is continued in the usual way. As indicated in Fig. 1, the end pipes 11 of the series are 95 inclined with respect to the other pipes to give a better lifting effect upon the curved portions of the sheet adjacent its side edges. Various other arrangements might obviously be provided for accomplishing the function of cooling the advance edge of the sheet and lifting it slightly, the invention not being limited to the particular arrangement shown or to the particular angle illustrated for applying the air blasts, although this is the arrangement which is preferred.

100

What I claim is:

1. A process for holding up the advance edge of a plastic sheet of glass as it passes from a forming roll onto a runway which consists in applying a blast of fluid between 105 the forming roll and the advancing end of the sheet to lift such end as it passes onto the end of the runway.

2. A process for holding up the advance edge of a plastic sheet of glass as it passes 110

from a forming roll onto a runway which consists in directing a blast of fluid toward the advancing end of the sheet and onto the surface of the roll in advance of such end so as to lift the end preliminary to its passage over the end of the runway.

3. A process for holding up the advance edge of a plastic sheet of glass as it passes from a forming roll onto a runway which 10 consists in applying a blast of air in a direction opposite to that of the advance of the sheet and between the end of such sheet and the roll so as to lift such end during its passage over the forward end of the runway.

15 4. In combination in apparatus for making sheet glass, including a pair of rolls between which the glass is sized or rolled to the desired thickness, a runway for receiving the glass from the lower roll and means for 20 directing a blast of fluid beneath the advancing end of the sheet preliminary to its movement over the end of the runway.

5. In combination in apparatus for mak-

ing sheet glass, including a pair of rolls between which the glass is sized or rolled to 25 the desired thickness, a runway for receiving the glass from the lower roll, a pipe extending transversely of the roll adjacent the end of the runway and opening toward the surface of the roll, and means for supplying 30 fluid under pressure to the pipe to provide a blast of fluid toward the advancing end of the sheet.

6. In combination in apparatus for making sheet glass, including a pair of rolls between which the glass is sized or rolled to the desired thickness, a runway for receiving the glass from the lower roll and means for directing a blast of fluid toward the advancing end of the sheet and against the 40 surface of the roll to chill such end of the sheet and force the fluid therebeneath.

In testimony whereof, I have hereunto subscribed my name this 29th day of November, 1927.

DOMINIC F. CANNON.
